Des. 182,035
Patented Feb. 4, 1958

182,035

SEWING MACHINE

Phillip S. Morse, New York, N. Y.

Application February 5, 1957, Serial No. 44,765

Term of patent 14 years

(Cl. D70—1)

FIG. 1

FIG. 2

FIG. 3

FIG. 4

FIG. 5

Fig. 1 is a front perspective view of a sewing machine showing my new design;

Fig. 2 is a rear perspective view thereof;

Fig. 3 is a top view thereof;

Fig. 4 is an end perspective view taken from the left end of Fig. 1; and

Fig. 5 is an end perspective view taken from the right end of Fig. 1.

I claim:

The ornamental design for a sewing machine, substantially as shown.
